DESIGN FOR A STAND FOR FUEL DRUMS OR THE LIKE

Adelard Boilard, Indian Orchard, Mass.

Application October 21, 1933. Serial No. 49,530

Term of patent 3½ years

To all whom it may concern:

Be it known that I, ADELARD BOILARD, a citizen of the United States, residing at Indian Orchard, in the county of Hampden and State of Massachusetts, have invented a new, original, and ornamental Design for a Stand for Fuel Drums or the like, of which the following is a specification, reference being had to the accompanying drawing, forming part hereof.

Fig. 1 is a front elevational view of the stand showing my new design.

Fig. 2 is a plan view thereof.

Fig. 3 is a side elevational view of the stand shown in Fig. 1, and

Fig. 4 is a small scale perspective view of the stand shown in Figs. 1, 2 and 3.

I claim:

The ornamental design for a stand for fuel drums or the like as shown and described.

ADELARD BOILARD.
